UNITED STATES PATENT OFFICE.

WILLIAM L. GOODHUE, OF WHEELING, WEST VIRGINIA, ASSIGNOR TO AMERICAN SHEET & TIN PLATE COMPANY, OF PITTSBURG, PENNSYLVANIA, A CORPORATION OF NEW JERSEY.

SHEET-METAL PACKAGE.

No. 918,998.

Specification of Letters Patent.

Patented April 20, 1909.

Application filed October 27, 1906. Serial No. 340,870.

To all whom it may concern:

Be it known that I, WILLIAM L. GOODHUE, of Wheeling, Ohio county, West Virginia, have invented a new and useful Sheet-Metal Package, of which the following is a full, clear, and exact description, reference being had to the accompanying drawings, forming part of this specification, in which—

Figure 1 is a top plan view of my improved package; Fig. 2 is an end view of the same; and Fig. 3 is a partial perspective view of the binder or strip, on a larger scale.

The object of my invention is to provide a simple, cheap and effective binder for packages of corrugated sheets, which will provide for reducing storage space.

In the drawings, I show a pack of corrugated sheets 2 which are held together by two or more corrugated bands 3. These bands extend entirely across one face of the pile, and their opposite end portions 4, 4 are bent back on the opposite face and also corrugated to fit the sheets. The amount of the lap in the bent-back ends is shown as about one and one-half corrugations in length. This, however, may be varied as desired, and the number of bands may also be varied to any desired number.

The advantages of my invention result

from the reduced amount of storage space occupied by a set of these packages. One package can interfit with the next owing to the use of the corrugated strips, thus reducing the space occupied. This is of special value in transportation on shipboard where the freight charges depend largely on the space occupied. The corrugated binders are cheap, may be easily made, and effectually hold the sheets in the pile.

The number of the strips used, and the shape and form of the corrugations may be changed; and many other variations may be made without departing from the spirit and scope of my invention.

I claim:

A sheet metal package, comprising a pile of corrugated sheets held together by wholly external separated corrugated binder strips, said strips extending across one face of the pile and being bent back along the opposite face of the pile, the sheets of the pile all being in contact with each other; substantially as described.

In testimony whereof, I have hereunto set my hand.

WILLIAM L. GOODHUE.
